UNITED STATES PATENT OFFICE

131,700

DESIGN FOR A MATERIAL DISTRIBUTING DEVICE

Roy Gaddis, Cedar Rapids, Iowa, assignor to
Milver C. Erusha, Walford, Iowa

Application August 21, 1940, Serial No. 94,535

Term of patent 7 years

To all whom it may concern:

Be it known that I, Roy Gaddis, a citizen of the United States, residing at Cedar Rapids, in the county of Linn and State of Iowa, have invented a new, original, and ornamental Design for a Material Distributing Device, of which the following is a specification, reference being had to the accompanying drawing, forming part thereof.

Figure 1 is a view in perspective of a material distributing device embodying my new design, as

it would appear when mounted on the tail gate of a dump truck box with the box in dumping position, and

Figure 2 illustrates the same device as viewed from the opposite side and as it would appear upon a dump truck box in lowered position.

I claim:

The ornamental design for a material distributing device as shown.

ROY GADDIS.
